DESIGN FOR A FLUORESCENT LAMP

Michael Hallward, Marblehead, Mass., assignor to Hygrade Sylvania Corporation, Salem, Mass., a corporation of Massachusetts

Application September 7, 1940, Serial No. 94,848

Term of patent 7 years

To all whom it may concern:

Be it known that I, Michael Hallward, a citizen of Great Britain, residing at Marblehead, in the county of Essex and State of Massachusetts, have invented a new, original, and ornamental Design for a Fluorescent Lamp, of which the following is a specification, reference being had to the accompanying drawing, forming part thereof.

The figure is a side perspective view of a fluorescent lamp showing my new design.

I claim:

The ornamental design for a fluorescent lamp,
as shown.

MICHAEL HALLWARD.
